UNITED STATES PATENT OFFICE.

GEORGE E. RUTLEDGE, OF CHICAGO, ILLINOIS, ASSIGNOR TO VASSAR SWISS UNDER-WEAR COMPANY, OF CHICAGO, ILLINOIS, A CORPORATION OF ILLINOIS.

DESIGN FOR A BUTTON.

Application filed October 22, 1921. Serial No. 509,741. Term of patent 3½ years.

To all whom it may concern:

Be it known that I, GEORGE E. RUTLEDGE, a citizen of the United States, residing at Chicago, in the county of Cook and State of Illinois, have invented a new, original, and ornamental Design for Buttons, of which the following is a specification, reference being had to the accompanying drawing, forming part thereof.

Figure 1 is a perspective view of a button showing my new design;

Figure 2 is a plan view of the button;

Figure 3 is a section on the line 3—3 of Figure 2.

The design as shown, comprises a button in which the major portion of the face is substantially V-shaped. This is effected by cutting away portions of the button to produce the inwardly and downwardly inclined surfaces terminating at the straight sides of the V-shaped face.

I claim:

The ornamental design for a button, as shown.

GEORGE E. RUTLEDGE.
